United States Patent Office

Des. 225,103
Patented Nov. 14, 1972

225,103

HORSE BARN

Von A. Hardman, 1719 Alice Ave., Akron, Ohio 44310

Filed May 10, 1971, Ser. No. 142,098

Term of patent 14 years

Int. Cl. D25—03

U.S. Cl. D13—1

FIG. 1

FIG. 3

FIG. 2

FIG. 4

FIG. 1 is a perspective view showing my new design for a horse barn.

FIG. 2 is a top plan view thereof.

FIG. 3 is an end elevation taken from the top of FIG. 2.

FIG. 4 is a perspective view showing a modified form of my invention.

The opposed sides of the outboard wings shown in FIGS. 1 and 4 are identical to those illustrated therein.

I claim:

The ornamental design for a horse barn, as shown and described.
